UNITED STATES PATENT OFFICE.

JAMES C. COVERT, OF WEST TROY, NEW YORK.

DESIGN FOR A HOOK.

SPECIFICATION forming part of Design No. 24,664, dated September 10, 1895.

Application filed May 23, 1895. Serial No. 550,445. Term of patent 14 years.

To all whom it may concern.

Be it known that I, JAMES C. COVERT, a citizen of the United States, residing at West Troy, in the county of Albany and State of New York, have invented and produced a new and original Design for Hooks; and I do hereby declare the following to be a full, clear, and exact description of the same, reference being had to the accompanying drawings, forming a

part thereof.

This invention relates to a new and original design for a hook; and it consists in the special shape and configuration shown and hereinafter described.

In the drawings, Figure 1 designates a hook in rear perspective. Fig. 2 is a rear elevation. Fig. 3 is a side elevation, and Fig. 4 is a top plan view.

I have shown the design in the manner above indicated for the reason that the characteristic feature is located at the rear end of the hook.

In the drawings, A designates the hook, B the central part, and C the loop. On the upper central face of the forward cross-bar of the loop is a plate D directly at the rear of the part B. This plate has curved sides and top and at its center a curved opening b leading down from the top of the plate. The part B is cylindrical and the loop-sections are fashioned, as shown.

The essential feature of the design is the special shape shown.

Having thus described the invention, what I claim as new, and desire to secure by Letters Patent, is—

The design for a hook, substantially as herein shown and described.

In testimony whereof I affix my signature in presence of two witnesses.

JAMES C. COVERT.
